UNITED STATES PATENT OFFICE

139,615

DESIGN FOR A CHARM OR SIMILAR ARTICLE

James L. Reed, Central, N. Mex.

Application May 16, 1944, Serial No. 113,601

Term of patent 3½ years

(Cl. D45—17)

To all whom it may concern:

Be it known that I, James L. Reed, a citizen of the United States of America, residing at Central, county of Grant, and State of New Mexico, have invented a new, original, and ornamental Design for a Charm or Similar Article, of which the following is a specification, reference being had to the accompanying drawing, forming a part thereof wherein:

I claim:

The ornamental design for a charm or similar article, as shown.

JAMES L. REED.
